ORREN A. SAWYER, OF LOWELL, MASSACHUSETTS, ASSIGNOR TO DRAPER COMPANY, OF HOPEDALE, MASSACHUSETTS, A CORPORATION OF MAINE.

TAKE-UP MECHANISM FOR LOOMS.

SPECIFICATION forming part of Letters Patent No. 738,245, dated September 8, 1903.

Application filed June 20, 1903. Serial No. 162,299. (No model.)

To all whom it may concern:

Be it known that I, ORREN A. SAWYER, a citizen of the United States, and a resident of Lowell, county of Middlesex, State of Massachusetts, have invented an Improvement in Take-Up Mechanism for Looms, of which the following description, in connection with the accompanying drawings, is a specification, like characters on the drawings representing like parts.

In the high-roll form of take-up mechanism wherein the take-up or sand roll is located above the roll on which the cloth is wound it sometimes happens that the latter is not held with sufficient firmness or pressure against the take-up roll. For this reason, and it may be also due in part to other causes, the newly-made cloth will continue to stick to the take-up roll as it passes between it and the cloth-roll instead of being wound upon the latter, and the cloth is carried around indefinitely upon the take-up roll until torn or some other resulting trouble causes the fault to be noticed.

The present invention has for its object the production of means for effecting the operation of a signaling device to attract the attention of the weaver upon the occurrence of such a fault as above referred to, and provision is made to automatically effect the stoppage of the loom at such time.

The various novel features of the invention will be fully described in the subjoined specification and particularly pointed out in the following claims.

Figure 1 is a transverse sectional view of a portion of a loom taken between the cloth-roll supports, showing the take-up mechanism and with one embodiment of the present invention applied thereto. Fig. 2 is a front elevation of the mechanism shown in Fig. 1; and Fig. 3 is a top or plan view of a portion of the breast-beam, filling-detecting mechanism, and holding-plate for the shipper, the signaling device and the means for effecting its operation being shown in plan.

The take-up ratchet a^3 , actuating-pawl a^2 , the take-up or sand roll T , the cloth-roll T^x , Figs. 1 and 2, the filling-fork m^x , its slide m , mounted in a guide m' on the breast-beam, the weft-hammer W , having a hook w to en-

gage the tail m^2 of the fork to move the slide outward, and the knock-off lever n , Fig. 3, on the holding-plate N^x for the shipper N may be and are all of well-known or usual construction, outward movement of the fork-slide m operating the knock-off lever n to release the shipper from its holding-notch and effect the operation of a stopping instrumentality, all as usual.

The high-roll form of take-up illustrated is substantially such as is shown in United States Patent No. 610,636, the cloth C , Fig. 1, passing from the fell to the take-up roll T , partly around it and between it and the cloth-roll T^x , and being wound upon the latter, as provided for in said patent.

The fork-slide m is herein shown as provided with two upturned ears m^5 m^7 , and on the former, which is nearer the outer end of the slide, is mounted a lever e , a stud 5 projecting laterally from said ear over the side of the guide m' , Fig. 3. The outer end of the lever has pivoted to it a depending signal-actuator e' , having a widened foot e^2 , which is normally behind the upturned bent head s' of an arm s , fulcrumed at 6 on the loom-frame, said arm herein constituting a visual signal or indicator. Normally this signal is maintained in the position shown in full lines, Fig. 1, by a spring-clip s^x , the rear end of the head s' extending rearwardly over the breast-beam B . When the head is pushed forward sufficiently to release the arm s from the clip s^x , said arm will drop to dotted line, (operative position,) Fig. 1, a stop-lug s^2 on the lower end of the arm at such time engaging the loom-frame and holding the signal or indicator in abnormal extended position at the front of the loom.

Referring to Figs. 1 and 3, the ear m^7 has a pin 7 loosely extended transversely through it, and on the inner side of the ear said pin has fast upon it a lever f , downwardly extended outside the guide m' to form a feeler f^x , having a broadened foot f' to rest upon the cloth substantially directly above the axis of the take-up roll. Beyond the feeler the lever f is shown as longitudinally slotted at 8 to receive a pin 9 on the rear end of lever e , the normal position of the levers being clearly shown in Fig. 1, the feeler contacting

with the cloth. At the outer side of ear m^7 the pin 7 has secured to it an elongated finger f^2 , extended toward the back of the loom and above the filling-fork, the free end of the finger being shown in Fig. 1 as downturned at f^3 and normally held slightly above the head of the fork in front of its fulcrum by the weight of the feeler f^x and its lever or carrier f . Now if the cloth sticks to the take-up roll T and is carried around upon it the succeeding layers beneath will raise the cloth C as it passes to said roll, thereby lifting the feeler and rocking the pin 7 to depress the finger f^2 until its downturned end f^3 engages the fork-head and holds the tail m^2 down to be engaged by the weft-hammer hook w. At the same time the foot e^2 of the actuator e' is depressed into position behind the head s' of the signal or indicator s, and as the slide m is moved outward by the weft-hammer the actuator will engage the signal and release it from the spring-clip s^x , so that it will fall by gravity into signaling position. (See dotted lines, Fig. 1.) At the same time the slide m engages the knock-off lever n and releases the shipper N to effect stoppage of the loom. The foot e^2 extends in front of the outer end of the fork-slide, so that a positive outward movement is imparted to the actuator to effect the operation of the signal or indicator. Should the fork detect absence of filling in usual manner, the outward movement of the slide will effect the release of the shipper, as described, but as the foot e^2 of the actuator will be above the head s' of the signal the latter will not be thrown into signaling position. The weaver will thus know that the loom stopped from some cause other than winding up of the cloth on the take-up roll. The invention is not restricted to the precise construction and arrangements shown and described, as the same may be modified in various particulars without departing from the spirit and scope of the invention.

Having fully described my invention, what I claim as new, and desire to secure by Letters Patent, is—

1. In a loom, a cloth-roll, a take-up roll to effect the winding of the cloth thereupon, and an indicator operated automatically upon accumulation of the cloth upon the take-up roll.
2. In a loom, a cloth-roll, a take-up roll to effect the winding of the cloth thereupon, a visual indicator, and means operated auto-

matically upon winding of the cloth upon the take-up roll to move the indicator into abnormal position.

3. In a loom, a cloth-roll, a take-up roll to effect the winding of the cloth thereupon, an indicator, a device to hold it in non-indicating position, and means operated by or through accumulation of cloth upon the take-up roll to release said indicator and effect its movement into indicating position. 65

4. In a loom, a shipper to operate a stopping instrumentality, a holding device to retain the shipper in running position, take-up mechanism, including a take-up roll, and means operated automatically upon accumulation of cloth upon said roll to cause release of the shipper from its holding device. 70

5. In a loom, a shipper to operate a stopping instrumentality, a holding device to retain the shipper in running position, take-up mechanism, including a take-up roll, a visual indicator, means operated automatically upon accumulation of cloth upon said roll to cause release of the shipper from its holding device, and an actuator operated by said means to move the indicator into abnormal, indicating position. 75

6. In a loom, a shipper to operate a stopping instrumentality, filling-detecting means, including a slide, a shipper-releasing device 85 operated by the slide upon detection of absence of filling, take-up mechanism, including a take-up roll, means operated by accumulation of cloth on said roll to cause the actuation of said slide, an indicator, and actuating connections between it and the slide, rendered operative when the movement of the latter is due to cloth accumulation. 90

7. In a loom, a shipper to operate a stopping instrumentality, means to release the shipper upon detection of filling failure, take-up mechanism, including a take-up roll, means dependent upon an accumulation of cloth thereupon to cause release of the shipper, and an indicator moved automatically 100 into indicating position upon release of the shipper by said latter means.

In testimony whereof I have signed my name to this specification in the presence of two subscribing witnesses.

ORREN A. SAWYER.
